UNITED STATES PATENT OFFICE.

AMOS F. DIXON, OF NEWARK, NEW JERSEY, ASSIGNOR TO WESTERN ELECTRIC COMPANY, OF NEW YORK, N. Y., A CORPORATION OF ILLINOIS.

CALL-REGISTERING MECHANISM.

1,143,367.

Specification of Letters Patent. Patented June 15, 1915.

Application filed December 14, 1912. Serial No. 736,873.

To all whom it may concern:

Be it known that I, AMOS F. DIXON, a citizen of the United States, residing at Newark, in the county of Essex and State of New Jersey, have invented a certain new and useful Improvement in Call-Registering Mechanism, of which the following is a full, clear, concise, and exact description.

This invention relates to telephone toll devices and more particularly to a device wherein toll is collected and registration is made for each successful call.

The object of this invention is to provide a call registering mechanism in combination with a coin collecting apparatus which is simple in construction and efficient and reliable in operation. To accomplish this object electromagnetically operated means under the control of the coin distributing mechanism are provided whereby only successful calls or those for which a coin is collected are recorded by a suitable registering device.

This invention will be fully understood from the following description taken in connection with the accompanying drawing in which,

Figure 1 is a side elevation, partly in section, of a part of a coin collecting and registering device constructed in accordance with this invention; Fig. 2 is a side elevation of the coin collecting device with the inclosing housing and outer wall of the coin chute removed; Figs. 3 and 4 are detail views of the coin distributing mechanism showing the location of the various elements during the depositing and refunding operations; and Fig. 5 is the preferred system of connections shown diagrammatically.

A base plate 5 serves as the foundation for the coin distributing mechanism and registering device. Supported on the base plate 5 is a zig-zag coin chute 6 of the usual construction provided with coin collecting and coin return channels. An electromagnetic system composed of coils 7 and 8 is provided with a tilting armature 9 on which are located two fixed pins 10 and 11 and a spring pressed movable pin 12. The pins carried by the armature project into the coin chute 6 above the divergence of the deposit and refund channels and provide means for arresting a coin in its downward course for closing a break in the signal circuit and for

directing the arrested coin into either the deposit or refund channel. The armature and the pins carried thereby, therefore, comprise a movable coin distributor which is kept in a central or neutral position by means of levers 13 and springs 14.

The registering mechanism or service meter consists of an actuating coil 15 controlling a pivoted armature 16 to which is pivotally connected an actuating pawl 17. When attracted the armature 16 causes the pawl 17 to engage a ratchet wheel 18 to advance the register train 19. Upon the de-energization of coil 15 a spring 20 retracts the armature and pawl into a position where the next advance will again rotate the register train. A dog 21 engaging with the ratchet wheel 18 prevents the backward movement of the train.

The pin 10 is insulated from the armature and is connected to an insulated contact point 25 on the pivotal axis thereof by an insulated conducting strip 26. Mounted upon the base or frame of the mechanism in any suitable manner but insulated therefrom and from each other are two contact springs 27 and 28. The contact spring 27 is provided with a contact point 29 adapted to be engaged by a pin 30 carried by armature 9 when the same is rotated in a counter clockwise direction, as shown in Fig. 4, and is connected to one terminal of the coil 15 of the service meter by a conductor 31. The contact spring 28 is provided with a contact 32 engaging the contact point 25 when the armature is in a neutral position as shown in Fig. 5, but which is adapted to be removed from such engagement upon the tilting of the armature; and a contact 33 adapted to be engaged by the armature when the same is tilted in a clockwise direction, as shown in Fig. 3. The spring 28 is connected to one terminal of the coil 7 of the coin collector magnet by means of a conductor 34. The common terminal of coils 7 and 8 of the coin collector distributing magnet is connected to coil 15 by conductor 35, while the independent terminal of coil 8 is joined to the line wire L by a conductor 36.

When the armature is tilted in either direction the contact between points 25 and 32 is broken on account of the spring 28 being raised slightly from its normal position by contacting with the edge of the armature as

shown in Fig. 3 or the insulated buffer 37 as shown in Fig. 4. This contact is, however, not broken until the armature strikes the spring contact 28 or the pin 30 engages the contact 29 depending upon the direction of movement of the armature.

A source of energy 40 furnishes the energizing current for operating the system through a pair of keys 41 and 42.

- 10 In service a coin placed in the upper part of the chute 6 and released is arrested between pins 11 and 12 as shown in Fig. 2. The movable pin 12 contacts with the fixed pin 10 and a circuit is provided for the 15 grounded source of energy 40 as follows: Line L, conductor 36, coils 8 and 7, conductor 34, spring 28, contact points 32 and 25, conducting strip 26, pins 10 and 12 to ground. Consequently, when either key 41 20 or 42 is closed current will flow over the circuit just traced. If the call is successful key 41, for example, is operated sending positive current over the line to tilt the armature 9 in a counter-clockwise direction 25 as shown in Fig. 4. The coin is deposited breaking the contact between pins 10 and 12 and contact points 25 and 32. This breaking of the contacts, however, does not take place until the contact point 29 carried by 30 spring 27 has been engaged by pin 30 carried by the armature. A circuit is, therefore, formed from grounded source of energy 40, line L, conductor 36, coil 8, conductor 35, coil 15 of the service meter, conductor 31, spring 27, contact point 29, pin 30, armature 9 to ground. Current thus passes through the service meter coil which attracts its armature effecting the registration of the call. If, however, the call had 35 been unsuccessful, current of the opposite polarity would have been sent over the line to tilt the armature in a clockwise direction as shown in Fig. 3. The coin is released into the refund channel and the contact between pins 10 and 12 is broken as hereinbefore described. This contact, however, is 40 not broken until contact point 33 of the spring 28 engages with the armature 9. Current then passes from grounded source of energy 40, key 42, line L, conductor 36, coils 8 and 7, conductor 34, spring 28, contact 33, armature 9 to ground. It will thus be observed that when a coin is returned no current passes through coil 15 of the service meter and no call is recorded.

45 The coil 15 of the service meter being connected in a branch circuit which is substituted for one winding of polarized magnet when the coin distributor is operated to collect a coin, may therefore be operated from the same source of current as is used to operate the coin collecting magnet and over a portion of the same circuit, thus greatly simplifying the winding of the apparatus and avoiding the use of a second

source of energy for operating the register. Moreover, the actuating coil 15 will receive substantially the same amount of current as is passed through the windings 7 and 8 when the coin distributor is operated. This results in a more positive operation of the register 19 than would be obtained if the register was connected to operate from the coin distributor, since it is well known that a straight electromagnet will exert considerably greater pull upon its armature in response to a given energizing current than will be exerted upon a centrally pivoted armature of a polarized magnet in response to the same amount of energizing current.

What I claim is:

1. In a registering mechanism, a movable coin distributor, a polarized electromagnet comprising two coils for moving said distributor, a circuit for said polarized magnet, a register, an actuating coil therefor, and switching means controlled by the operation of said distributor for including said register actuating coil in a portion of the circuit over which said polarized magnet is energized.

2. In a registering mechanism, a movable coin distributor, a polarized electromagnet comprising two coils for operating said distributor, a circuit for said polarized magnet, a register, an actuating coil therefor, and switching means controlled by the operation of said distributor for connecting said register actuating coil in said circuit in substitution for one coil of said polarized magnet.

3. In a registering mechanism, a movable coin distributor, a polarized electromagnet comprising two coils for moving said distributor, a circuit for said polarized magnet, a register, an actuating coil therefor, and switching means controlled by the operation of said distributor for opening the circuit through one coil of said polarized electromagnet and including the register actuating coil in series with the other coil of said polarized magnet.

4. In a registering mechanism, a movable coin distributor, a polarized electromagnet comprising two coils adapted to move said distributor in one direction to refund and in the opposite direction to collect, a circuit for said polarized magnet, a register, an actuating coil therefor, and switching means controlled by the operation of said distributor in collecting to include said actuating coil in a portion of said circuit in substitution for one of said polarized magnets.

5. In a combined coin collector and service meter, a coin distributor movable in two directions, an electromagnet controlling said distributor, a circuit therefor, a register, an actuating coil therefor, a branch circuit including said register actuating coil, and switching means controlled by the move-

ment of said distributor in one direction for substituting said branch circuit for a portion of the circuit through said distributor operating magnet.

- 5 6. In a combined coin collector and service meter, an electromagnet, coin distributing mechanism controlled thereby, a circuit for said electromagnet, a register, an actuating coil therefor, and means controlled by the
10 operation of said coin distributing mecha-

nism for including said actuating coil in a portion of the circuit for said electromagnet.

In witness whereof, I hereunto subscribe my name this 13th day of December, A. D. 1912.

AMOS F. DIXON.
